United States Patent Office

Des. 219,001
Patented Oct. 20, 1970

219,001

DIRECTIONAL SIGN

Albert T. Hardy, 430 Techwood Drive NW, Apt. 902-C,
Atlanta, Ga. 30313

Filed July 3, 1968, Ser. No. 12,618

Term of patent 14 years

Int. Cl. D20—03

U.S. Cl. D96—12

The figure is a front elevation of a directional sign showing my design.

The conventional indicia is shown for illustrative purposes only and forms no part of the claim.

I claim:

The ornamental design for a directional sign, as shown and described.
